TRAFFIC CONTROL SIGN FOR HIGHWAY INTERSECTIONS OR THE LIKE

Christopher B. Sanford, 1328 N. 45th St.,
Milwaukee, Wis.

Filed Sept. 12, 1960, Ser. No. 62,114

Term of patent 14 years

(Cl. D72—1)

Fig. 1

Fig. 2

Fig. 3

Fig. 4

FIG. 1 is a front elevation of a traffic control sign for highway intersections or the like embodying my new design;

FIG. 2 is a front elevation of a modified form of the sign shown in FIG. 1;

FIG. 3 is a front elevation of a second modified form of the sign shown in FIG. 1; and

FIG. 4 is a side elevation of the sign.

The rear face of the sign is plain.

I claim:

The ornamental design for a traffic control sign for highway intersections or the like, substantially as shown and described.
